EDUCATIONAL DEVICE

Otto R. Eickmeyer and Catherine J. Pitt, both of
1212 18th Ave., Menominee, Mich.

Filed Nov. 18, 1960, Ser. No. 62,891

Term of patent 14 years

(Cl. D25—1)

FIG. 1.

FIGURE 1 is a perspective view of an educational device, showing our new design, and

FIGURE 2 is an elevational view, as viewed from one end.

The essential features of our design reside in the portion shown in full lines.

We claim:

The ornamental design for an educational device, as shown and described.
